CLAIM

The ornamental design for an ice cube tray, as shown and described.

DESCRIPTION

FIG. 1 is a top view of an ice cube tray with top and bottom parts in a separated position showing my new design; FIG. 2 is a front elevational view thereof;

FIG. 3 is a top plan view thereof;

FIG. 4 is a left view thereof;

FIG. 5 is a rear elevational view thereof;

FIG. 6 is a bottom plan view thereof;

FIG. 7 is a right view thereof;

FIG. 8 is a perspective view thereof; and,

FIG. 9 is another perspective plan with top and bottom parts in a separated position view thereof.

The broken lines illustrate portions of the ice cube tray that form no part of the claimed design.
